[57] ABSTRACT

A microwave gas discharge switching tube is provided with a conductive wire grid mounted on the inside of its input window to shorten the recovery time following the termination of a heavily ionised gas discharge within the tube. The tube may additionally contain water vapour in known manner to further reduce the recovery time.

FIG. 1.

FIG. 2.

MICROWAVE GAS DISCHARGE SWITCHING TUBES

This invention relates to microwave gas discharge switching tubes. Microwave gas discharge switching tubes are used in waveguide systems involving the transmission to an aerial of high energy microwave pulses from a transmitter and the transmission of low energy signals received by the aerial to a receiver. The purpose of the gas discharge switching tube, or duplexing tube, as it is commonly called, is to isolate the receiver from the transmission system during the transmission of the high energy microwave pulse from the transmitter. Examples of such tubes are TR tubes, ATR tubes, pre-TR tubes and so forth. The required isolation is achieved by a heavily ionised gas discharge initiated and sustained by the high energy microwave pulse from the transmitter, which gas discharge acts as an electrical shutter diverting the energy from one channel to the other. The speed with which the "shutter" can be opened following a high energy pulse from the transmitter is known as the recovery time and is dependent upon the speed with which the ionised gas discharge can be quenched.

For obvious reasons the recovery time is required to be as short as possible.

One known method of quenching the discharge is to include in the gas filling of the tube an agent with a high affinity for electrons. Usually this agent is water vapour. Whilst this results in an improved recovery time the method suffers from the disadvantage that the satisfactory life of the tube is dependent upon the length of time that the required partial pressure of the water vapour can be maintained, and it is found in practice that the water vapour gradually disappears during operation. In addition, if the partial pressure of the water vapour is initially increased to increase the satisfactory life of the tube the leakage through the tube also increases. Furthermore, whilst the water vapour quenches the discharge sufficiently rapidly for signals to be detected at the receiver, ionisation tends to decay over a prolonged period and, in fact, persists for several microseconds. This prolonged decay of the low density ionised gas gives rise to a continual change of phase in the tube which, for many applications, is unacceptable.

Many microwave discharge gas tubes include a primer or keep-alive electrode and in order to avoid the aforementioned difficulties it has been suggested that the keep-alive electrode be located behind the input window. Such an arrangement is, for example, described on page 73 et seq. of "Microwave Gas Discharge Devices" by A. Kraszewski, published by Iliffe, 1967. Locating the keep-alive electrode behind the input window, however, involves a number of design and production difficulties and furthermore, for broad-band tubes the voltage which has been found necessary to achieve satisfactory recovery times is undesirably high.

The object of the present invention is to provide improved microwave gas discharge switching tubes of satisfactory recovery time.

According to this invention, a microwave gas discharge switching tube includes a conductive structure connected across and in close proximity to the input window of said tube, said structure being so dimen-

sioned and arranged as to present a negligible de-tuning admittance to a microwave signal in operation.

Preferably said structure is in contact with said window.

5 Normally said structure is connected mechanically to a waveguide section forming the body of said tube. The structure may be electrically connected to the waveguide section or it may be electrically isolated therefrom. In this latter case the structure may be, of course, 10 arranged to have a voltage applied to it but this is not preferred.

Normally said window is mounted in the waveguide section by means of a window frame in which case said structure may be connected across said window frame.

15 Said structure may consist of a wire or a grid or the combination of a grid fixed to a wire, which wire is connected across said window, said grid usually extending perpendicularly to the plane of said window.

20 Whilst the tube described above may be used on its own, as with the known tube it may be combined with a varactor limiter or any other solid state device. The tube may also be of the primed or primerless type and with any of the known combinations of internal and external tuning elements.

25 The invention is illustrated in and further described with reference to the accompanying drawing in which,

FIG. 1 is a part cut away side elevation of a microwave gas discharge switching tube in accordance with the present invention and,

30 FIG. 2 is a section along the line AA of FIG. 1.

Referring to the drawing, in this case a TR tube for X-band frequencies consists of a section of wave-guide 1 having an input flange 2 and an output flange 3. 35 Mounted in input flange 2 is an input window 4, whilst mounted in output flange 3 is an output window 5. The two windows are mounted in window frames 6 and 7 respectively. Tunable cones 9, together with irises 10 constitute the tuning members for the tube. 11 is an exhaust tail by which the tube is evacuated. 12 is the primer or keep-alive electrode cone assembly. The interior of the device includes a gas filling.

40 As so far described the device is as known per se.

In accordance with the present invention a conductive structure is connected across the input window 4 of the tube. This conductive structure consists of a wire 13 to which is secured a grid 14. The wire 13 is mechanically connected to the window frame 6 in electrical contact at 15 and 16. The grid 14 extends perpendicularly to the plane of the input window 4 and is so dimensioned as to present a negligible detuning admittance to the microwave signal handled by the tube in operation.

55 In operation the conductive structure consisting of wire 13 and grid 14 acts to remove electrons from the decaying discharge during the recovery period by a probing action. The effect of the structure is more marked at lower levels of ionisation. If, therefore, as is possible, the known expedient of introducing water vapour into the tube is also used, the structure acts to reduce the otherwise prolonged time for decay of the low density ionised gas towards the end of the recovery period, which as was mentioned hereinbefore, is a characteristic of the use of water vapour alone. Thus the undesirable phase change which is a feature of the conventional tube using water vapour alone is reduced.

60 I claim:

1. In a microwave gas discharge switching tube including a body defining a wave guide section and having an input window; a conductive structure connected across and in close proximity to said input window, said structure being so dimensioned and arranged as to 5 present a negligible de-tuning admittance to a microwave signal in operation.

2. A tube as claimed in claim 1 and wherein said structure is in contact with said window.

3. A tube as claimed in claim 2 and wherein said 10 structure is connected mechanically to said body of said tube.

4. A tube as claimed in claim 3 and wherein said structure is electrically connected to said body.

5. A tube as claimed in claim 3 and wherein said 15 structure is electrically isolated from said body.

6. A tube as claimed in claim 3 and wherein said window is mounted in said waveguide section by means of a window frame and said structure is connected across said window frame.

7. A tube as claimed in claim 2 and wherein said structure consists of a wire or a grid or a combination of a grid fixed to a wire, which wire is connected across said window.

8. A microwave gas discharge switching tube comprising, in combination:

a body defining a waveguide section, an input closure at one end of the waveguide section having an input window opening, an output closure at the other end of the waveguide section having an out- 30

put window opening and microwave transparent input and output windows respectively closing said input and output window openings whereby to define a hermetically sealed cavity containing ionizable gas adapted to initiate and sustain a heavily ionized gas discharge in response to a high energy microwave signal input through said input window; and

means for quenching said gas discharge rapidly upon termination of the high energy microwave signal and for suppressing prolonged decay of low density ionized gas, said means including a conductive structure in close proximity to said input window and extending across said window essentially centrally thereof for effecting said suppression of prolonged decay of low density ionized gas; said structure being dimensional to present negligible de-tuning admittance to microwave signal input.

9. A microwave gas discharge switching tube as defined in claim 8 wherein said means also includes water vapor within said cavity for effecting the rapid quenching of the gas discharge.

10. A microwave gas discharge switching tube as defined in claim 9 wherein said conductive structure is a wire.

11. A microwave gas discharge switching tube as defined in claim 10 wherein said conductive structure also includes a grid fixed to said wire and extending therefrom in a plane normal to said input window.
